UNITED STATES PATENT OFFICE.

CLINTON GUYER AND PETER BROSIUS, OF MUNCY, PENNSYLVANIA.

WEATHER-STRIP.

SPECIFICATION forming part of Letters Patent No. 367,755, dated August 2, 1887.

Application filed April 8, 1887. Serial No. 234,205. (No model.)

To all whom it may concern:

Be it known that we, CLINTON GUYER and PETER BROSIUS, citizens of Pennsylvania, residing at Muncy, in the county of Lycoming and State of Pennsylvania, have invented certain new and useful Improvements in Weather-Strips; and we do hereby declare the following to be a full, clear, and exact description of the invention, such as will enable others skilled in the art to which it appertains to make and use the same.

Our invention relates to weather-strips; and its object is to provide an inexpensive self-adjusting article of manufacture, such as will meet the demands of the times and effectually prevent rain, snow, or cold air entering beneath doors.

It consists of a simple combination and arrangement of parts, such as will be more fully described hereinafter.

In the accompanying drawings, forming a part of this specification, Figure 1 is an external view of weather-strip attached to door-closed. Fig. 2 is an inner side view of weather-strip detached from door. Figs. 3, 4, 5, 6 are detail views of different parts which constitute our invention.

Similar letters refer to similar parts throughout.

Molding A is made of suitable wood, preferably with beads on front, an offset, and an inclined plane from the top, which answers the purpose of a water-shed and prevents rain from being forced or beaten in between molding and door. Any other suitable molding may be used. At the lower edge of molding A are two staples, a a, for attaching same to drop B, and in center on outer surface is fastened check or stop J. On the inside of molding A, at the end which closes against the door-jamb, is an aperture through which passes push-bar C, which leads to an indenture in molding A adapted to the working of the different parts of my invention.

Drop B consists of a piece of wood with an inclined surface on outer side, which forms a continuous water-shed for molding A, and is secured to molding A by means of two staples which interlock with staples a a, thereby forming a hinge. In the upper part of drop B are two staples, b b, in which works side bar, D.

The upper edge of drop B is beveled, and so arranged as to adapt itself thoroughly to molding A, which is similarly constructed.

Push-bar C is round, and made of malleable iron, with an elbow at one end in which is a slot wherein is located wheel E. In the rear end of push-bar C is a slot, e, in which arm F works, and it is held to its place by means of an iron pin, d, passing through both, and also staple f, which holds it firmly in molding A, giving ample room to work.

Wheel E is made of iron and works upon pivot e, which turns when door is closed, owing to coming in contact with wedge G. The turning of wheel E prevents friction and facilitates the closing of door.

Springs H H, made of helically-coiled metallic wire, pass around push-bar C and are held to their places by staple f and also by two iron pins, g g, and four washers, h h h, and elbow of arm F.

Arm F is made of malleable iron with opening i, through which passes screw j into semi-circular shoulder of side bar, D. Through the elbow of arm F is a rivet, k, with washer l, which holds it firmly to molding-plate I, allowing space for motion. In the upper end of arm F is iron pin d, which secures it to push-bar C.

Side bar, D, is made of suitable metal, with round ends and semicircular shoulder in center, through which passes screw j. It is held in place by staples b b.

Molding-plate I is fastened to molding A by means of two screws, and consists of thin piece of iron, as shown.

Wedge G consists of a piece of metal secured to door-jamb by one or more screws, with beveled edge toward inner part of door-jamb, so as to be instrumental in forcing back push-bar C when door is closed, which, in connection with other parts heretofore described, controls the adjustment of drop B.

Stop or check J consists of flat piece of metal fastened securely to molding A, one end curved outward, and its object is to form check or stop for drop B and to prevent its warping.

When door is closed, the elbow of push-bar C, in which is located wheel E, comes in contact with wedge G. This forces back push-bar C in combination with spiral springs H H,

arm F, and side bar, D, which forces drop B down closely, so as to effectually prevent rain, snow, or air from entering under the door. In a similar way, when door is opened, push-bar 5 C (in combination with spirals H H, arm F, and side bar, D) is forced back, owing to spirals H H assuming their natural position, and drop B again assumes its position for the closing of door.

16 Having thus fully described our invention, what we claim as new, and desire to secure by Letters Patent, is—

1. A weather-strip consisting of molding A, stop J, attached to center of same, drop B, 15 secured to the molding by means of staples a a, interlocking with similar staples of drop B, in combination with wedge G and horizontal push-bar C, with spiral springs H H, coiled around push-bar C and secured by pins g g 20 and washers h h h, wheel E, located in a slot upon pivot e in the forward end of push-bar C, plate I on the molding, side bar, D, arranged in staples b b to slide on the drop- plate, and lever F, pivoted to the plate I, and

having one arm connected to the inner end of bar C and the other to bar D, all substantially as described, and for the purpose set forth.

2. Wedge G, in combination with molding A, drop B, secured thereto by means of staples interlocking with similar staples, a a, of molding A, stop J, attached to center of molding A, horizontal push-bar C, with spiral springs H H, coiled around push-bar C and secured by pins g g and washers h h h, wheel E, located in a slot upon pivot e in the forward end of 35 push-bar C, plate I on the molding A, side bar, D, working in staples b b on the drop B, and lever F, pivoted to plate I, and having one arm pivoted to the inner end of bar C and the other to bar D, substantially as described and shown. 40

In testimony whereof we affix our signatures in presence of two witnesses.

CLINTON GUYER.
PETER BROSIUS.
